UNITED STATES PATENT OFFICE

HEINRICH JULIUS MÜLLER, OF SCHAFFHAUSEN, SWITZERLAND

ADJUSTABLE INVALID COUCH

Application filed May 16, 1928, Serial No. 278,100, and in Germany May 27, 1927.

The present invention relates to adjustable invalid couches and the like of the kind in which a positioning bar with a slot toothed along one side is pivoted on each side of the adjustable foot part, and supporting pins for the positioning bars are provided on the framework of the bed.

The object of the invention is to simplify the manipulation of the adjustable part of the invalid's bed.

This purpose is attained according to the invention by the adjusting bars being disengagable from the supporting pins secured to the framework of the bed, against the pull of a spring, by means of a member arranged in the neighbourhood of the usual handle provided on the foot part and capable of being actuated by the hand gripping the handle, the said member being connected to the toothed positioning bars by a lever and rod mechanism.

The adjustable invalid's bed according to the invention is suitable both for private bedrooms as well as for hospitals, as the parts projecting downwards over the frame are not visible to the ordinary observer; it also works with absolute reliability and is noiseless when correctly actuated.

The accompanying drawings show two constructional examples of the invention:

Figures 1 and 2 show a first example of the adjusting appliance, with the reclining surface stretched out,

Figure 3 in partial end elevation,

Figures 4, 5 and 6 with the head part raised, and accordingly with the foot part shifted upwards into low, horizontal, and uppermost positions respectively;

Figures 7 and 8 are views of a second example corresponding to Figures 2 and 3.

In these drawings 1 denotes the lower carrying frame of the composite under-mattress, which is placed upon a bedstead. 13 denotes the head part, which is rotatable about

50 pivots 12, and 17 denotes the seat part, which is rotatable about pivots 14 and which is pivotally connected with the head part 13 by means of intermediate members 15 and 16 guided by a link rod 18, and 3 denotes the foot part pivoted to the said seat part. 55 On each side piece of the foot part 3 there is an angle-shaped positioning bar 5, with guiding slot 6, and with locking teeth 7 arranged on one longitudinal edge of the said slot. The two positioning bars 5 are connected with one another by a transverse rod 50. To each side part of the carrying frame 1 is secured a small bearing block 8, with supporting pins 9 engaging in the slot 6.

In the cross piece 10 of the foot member 3 60 is slidably supported quite close to the usual handle 11 a peg 23 provided with a pressing knob 22, the lower end of the said peg being pivoted to one arm of a bell-crank lever 24 mounted on the cross piece 10. The other 65 arm of this lever is connected by a link rod 25 with the transverse rod 50. A spring 26 tends to pull the rod 25, together with the positioning bars 5, towards the left, to engage the locking teeth 7 with the peg 9, and to raise 70 the pressing peg 23.

The adjusting apparatus described operates in the following manner:—

In Figure 1 the reclining surface is arranged in an ordinary recumbent position. 75 If it is brought into a sitting position according to Figure 4, the foot member 3, which is oscillatably supported by means of the toothed positioning bars 5 upon the supporting pivots 9, descends of itself.

If it is desired when in a sitting position to have the feet supported at a higher level, as shown in Figure 5, or at the highest possible level, as shown in Figure 6, the foot member is raised by the handle 11, the teeth of the locking bars 5 snapping over the supporting pins 9. In the desired position of the foot member the handle 11 is released, whereupon the locking teeth 7, under the pull of the 90

springs 26, are drawn towards the supporting pins 9, and the foot part 3 is locked.

If conversely it is desired to bring the raised feet into a lower position, pressure is exerted with the thumb, while the foot member 3 is somewhat raised with the other fingers on the handle 11, upon the pressing knob 22 of the pin 23, whereby the locking bars 5 are lifted by means of the bell-crank lever 24, the rod and the cross bar 50, out of the teeth 7, so that the supporting pins can traverse the slots 6 in the locking bars 5, and a free upward or downward movement of the foot member 3 is rendered possible, as illustrated in Figure 5.

By pressing upon the pressing knob and the pins 22 and 23, the clicking noise of the teeth 7 can be prevented when the foot member 3 is being raised.

It is obvious that with the construction of the adjusting apparatus described, a high or a low positioning of the foot member is possible with any position of the head member, and a locking thereof in the adjusted position is also possible with one hand, without the foot member first having to be brought into its highest position for the lowering. The supporting pin 9 serves not only as an elevation supporting point but also as a pivot during the horizontal displacement of the foot member. By this means the manipulation is considerably simplified, and can be carried out in a shorter time.

In the case of the constructional example according to Figures 7 and 8, the handle 11 has in cross section the shape of an inverted U, and in this handle is displaceably arranged a gripping piece 27 carrying the pin 23. The lower end of the pin 23, as in the case of the first example, is connected with the bell-crank lever 24, which however is here turned through 180° as compared with Figure 1.

Upon taking hold of the handle 11 with the hand, the gripping piece 27 is also seized, and is pushed deeper into the handle 11, whereby the rod 25 is shifted towards the right, and the positioning bar 5 is disengaged. Upon the handle 11 being released a spring 26 pulls the gripping piece 27 down again and pulls the locking bar into engagement with the supporting pin 9. In the case of this example all the fingers can be employed for raising or lowering the foot member, whereby the security of grip is enhanced.

What I claim is:

In an adjustable invalid couch and the like, comprising a supporting frame, a rest arranged above the frame, a positioning bar on each side of the rest and having a slot toothed along one side, supporting pins on the frame and with which the positioning bars are normally engaged at their toothed and slotted portions, a handle on the rest, a vertically movable and pressable peg adjacent to the handle, a bell-crank lever pivoted to

the rest and connected to the peg, a longitudinal bar also pivoted to the other end of the said bell crank lever, a cross bar connecting the positioning bars and operably connected with the other end of the longitudinal bar, and the peg, bell-crank lever, longitudinal bar and cross bar being adapted to disengage the positioning bars from said pins when the said handle is gripped and pressure is exerted upon the peg.

In testimony whereof I have affixed my signature.

HEINRICH JULIUS MÜLLER.
